Assistant Examiner — Catherine Ho

(57) **CLAIM**

The ornamental design for a servo, as shown and described.

DESCRIPTION

FIG. 1 is a first perspective view of a servo showing our new design;
FIG. 2 is a second perspective view of the servo showing our new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

All broken line portions of the figure drawings are included to show portions of the article that form no part of the claimed design.

1 Claim, 8 Drawing Sheets(56)
